MACHINE FOR FINISHING CARPETS AND RUGS

Richard G. Knowland, Longmeadow, Mass., and Wellesley B. Cooper, Amsterdam, N. Y., assignors to Bigelow-Sanford Carpet Co., Inc., Thompsonville, Conn., a corporation of Massachusetts

Application November 18, 1931, Serial No. 575,765

4 Claims. (Cl. 26—2)

This invention relates to machines for treating the pile of carpets and rugs to impart an improved finish thereto.

Pile carpets and rugs as ordinarily made have the pile surface formed of twisted pile yarns secured to a backing fabric to provide rows of tufts projecting from the backing fabric. This row arrangement of the tufts remains more or less apparent in the finished fabric, and in many cases the backing fabric will "grin through", thus detracting from the appearance of the carpet or rug during use.

It has been proposed heretofore to brush the pile of a carpet or rug to remove the loose fibres and to cause the pile forming tufts to "stand up", but these prior treatments do not remove the row appearance of the tufts or prevent the backing fabric from showing through the pile, particularly in the cheaper weaves.

The present invention is directed to a machine for improving the finish of the pile of carpets and rugs to produce a smooth, homogeneous pile surface of superior appearance, feel and covering properties.

The pile tufts of carpets and rugs are formed of twisted yarns and the yarns are usually composed, in whole or in part, of woolen fibres, which possess a felting character when subjected to a rubbing action in the presence of heat and moisture. An important feature of the present invention, therefore, resides in a rubbing member or platen adapted to operate upon the heated and moist pile surface, and in actuating mechanism for operating the member or platen so that it will remove the twist from the ends of the pile yarns and interlock or felt the fibres of the adjacent tufts together while they are in a heated and moist condition, to impart to the pile a smooth, uniform surface that eliminates the usual "row effect" and produces a more complete coverage of the backing fabric.

The carpet or rug may be subjected to the finishing operation at any stage in the line of production, as for example, prior to the final shearing, but in any event the present invention contemplates a construction in which the pile surface is subjected to a heating and moistening operation to first condition the pile and then subject it to a massaging or felting treatment.

In accordance with the present invention the carpet or rug is preferably advanced through a steaming mechanism and then to a pile surface rubbing and pressing member, the degree of pressure being such only as to cause a felting action

of the projecting ends of the woolen fibres without matting or crushing down the pile surface.

The various features of the invention and novel combination of parts will be further understood from the following description when read in connection with the accompanying drawings, illustrating one good practical form of the invention.

In the drawings:—

Fig. 1 is a perspective view with parts broken away of a carpet and rug finishing machine, constructed in accordance with the present invention;

Fig. 2 is a longitudinal, vertical, sectional view through the delivery end of the machine of Fig. 1;

Fig. 3 is a vertical, sectional view taken on the line 3—3 of Fig. 2;

Fig. 4 is a longitudinal, sectional view through a pile carpet or rug showing the appearance of the pile tufts before they are treated in accordance with the present invention;

Fig. 5 is a similar view showing the carpet or rug of Fig. 4 after the ends of the pile forming yarns have been felted together in accordance with the present invention; and

Fig. 6 is a top plan view of the rubbing member or platen illustrating the type of movement imparted thereto.

The mechanism for carrying out the features of the present invention may be variously constructed and in the embodiment of the invention illustrated in the drawings, the operative parts of the machine are supported by the side frames 1, which are spaced sufficiently to accommodate the width of the carpet or rug to be treated, and are secured in spaced relation to each other by the transversely extending rods or braces 2.

The carpet or rug F to be finished in accordance with the present invention is fed to the machine of Fig. 1 over the roller 3 rotatably supported at the end of the machine by the brackets 4, and may be supplied from any suitable source.

It is important that the pile surface of the carpet or rug be delivered to the rubbing or massaging means in a heated and moist condition, a result which is accomplished in the construction shown by providing the steam box 5, mounted upon the machine frame by the hangers 6, the ends of which are bent around the transversely extending bearings or braces 7, and the steam box is provided with the side and end walls 8. Within the steam box is a series of steam pipes 9, having the steam discharge apertures 10 which, preferably, are arranged so as to direct the steam

jets laterally or downwardly away from the carpet or rug F to prevent marking the same. It will be apparent, however, that other means for heating and moistening the pile may be employed.

5 As the fabric F is advanced lengthwise of the machine over the steam box 5 it is supported by the perforated upper surface or covering 11 of the steam box, and is advanced through the machine by the spiked roller 12 rotatably supported 10 by the brackets 13. The spiked roller is driven by any suitable means such as the worm wheel 14 having the cooperating worm 15 upon the shaft 16, which shaft is driven by the bevel gears 17 from the power shaft 18 rotatably supported by 15 the brackets 19 in the lower portion of the machine.

In the construction shown the steam which passes from the steam box upwardly through the carpet or rug is collected in the hood 20 having 20 the upwardly extending discharge pipe 21, and the moisture that collects in the steam box 5 may be carried off by a drain, not shown.

The fabric F in the construction shown passes directly from the steam treatment just mentioned 25 to the rubbing or massaging mechanism and is preferably supported while its upper surface is being subjected to the rubbing operation. The supporting means provided for this purpose in the construction shown comprises a board or the 30 like 22, which is supported transversely of the machine below the pile rubbing member or platen 23. It is desirable to provide means for effecting a relative adjustment between the board 22 and platen 23 to accommodate fabrics of different 35 thicknesses, and to vary the pressure of the platen 23 upon the pile surface, and while it is apparent that the desired adjustment may be secured by raising or lowering either the board 22 or platen 23, in the construction shown, provision is 40 made for vertical adjustment of the fabric supporting member 22. This adjustment is secured in the construction shown by providing at the lower face of the board 22 the metal plate or plates 24, the ends of which project a short distance beyond the ends of the board 22, as clearly 45 shown in Fig. 3.

The ends of the plate 24 are adjustably supported from the upper flanges of the side frames 1 by the bolts 25, the tapered heads of which are 50 countersunk in the flanges just mentioned, and the bolts are rigidly secured to the flanges by locked nuts 26. The bolts 25 extend through holes in the plate 24 and this plate is yieldingly 55 and adjustably supported by the coiled springs 27 confined between the lower adjusting nuts 28 and under face of the plate 24; the upward movement of the plate 24 under action of the compressed spring 27 being limited by the adjusting nuts 29.

60 In the form of pile carpet or rug illustrated in the drawings the twisted pile yarns 30 are secured to the backing fabric by looping these yarns about the upper wefts 31, and the upper wefts 31 are bound to the lower wefts 32 by the chain warps 33, the upper and lower wefts being separated by the stuffer warps 34.

In order to secure the improved finish of the present invention it is important that the movement imparted to the rubbing member or platen 65 23 shall serve to untwist the pile yarns 30 and also to effect an interlocking or felting of the end fibres of the adjacent yarns together while in a heated and moist condition.

While different forms of movements may be 70 employed to secure the desired result, the platen

23, in the construction shown, is given a combined rotating and reciprocating movement, the rotation being in a direction to untwist the yarns. This desired movement is imparted to the platen 23 in the construction shown through the employment of eccentrics 35, two such eccentrics being shown, but a greater number may be employed where a relatively wide machine is used. The eccentrics 35 are rigidly secured to the lower ends of the vertical shafts 36, which are 80 journaled in bearings 37 secured to the spaced transversely extending beams 38. The beams 38, in the construction shown, have their opposite ends bolted to the I-beams 39, which are bolted to the angle irons 40 that are rigidly secured to the upper flanges of the side frames 1.

85 Rotative movement is imparted to the vertical shafts 36 by the bevel gears 41 that mesh with the bevel gears 42. The gears 42 are secured to the transversely extending shaft 43 which is journaled in bearings provided upon the brackets 44, which brackets are secured to the transversely extending beams 38. The shaft 43 in the construction shown is driven from the lower or power shaft 18 by the sprocket chain 45 which 90 passes around the lower sprocket 46 and upper sprocket 47.

95 The eccentrics 35 serve not only to operate the plate 23, but also to support its weight and to absorb the upward thrust of the platen when 100 in actual operation. The eccentrics 35 operate in the eccentric sleeves or bearings 48 rigidly mounted within the blocks 49 secured to the upper face of the platen 23. The bearing 48 preferably has an inwardly extending annular 105 flange 50 at its lower end adapted to engage the lower end of the eccentric 35 while the eccentric is rotatably retained within the sleeve 48 by the upper plate 51.

110 The main power shaft 18 may be driven from any suitable source of power, not shown, and serves to operate the eccentrics 35 at a much higher speed than the spiked roller 12, so that the pile fabric will be subjected to repeated rubbing actions as it is advanced over the work support 22.

115 The platen 23 is shown as having a flat lower face but this face may be rounded or given other shapes, and it is found in practice that good results are secured by covering the lower face 120 of the platen with a ribbed sheet of rubber; however, woven fabric or other covering material may be used to produce the desired felting of the woolen fibres. While only one platen is shown in the embodiment of the invention illustrated, 125 two or more platens may be employed on the same machine when it is desired to increase the rubbing or felting action, and in some cases it may be desirable to employ a pair of platens and operate them so that any tendency of one platen 130 to shift the fabric laterally will be counteracted by the movement of the other platen at that instance in the opposite direction.

135 The carpet or rug after being treated in accordance with the present invention may be 140 passed to the usual drying mechanism, not shown, to permanently lock the woven fibres in the felted condition of Fig. 5.

145 It will be seen from the foregoing that the twisted pile yarns 30 are delivered to the rubbing member or platen 23 in a heated and moist condition, and that the rubbing movement imparted to the platen 23 as it lightly presses upon the pile surface is such that it will remove the twist from the tuft forming yarns of Fig. 4, spread 150

out or separate the fibres at the ends of the yarn, and cause the fibres of adjacent yarns to interlock and felt together, as shown in Fig. 5. Thus the pile face of the rug or carpet is given

5 a smooth, homogeneous surface that eliminates the row appearance of the tufts, and forms a more complete coverage for the backing fabric so that it will not "grin through", and imparts an improved feel and lustre to the pile surface.

What is claimed is:—

- 10 1. In a machine for treating the pile surface of carpets and rugs to felt together the woolen fibres of the pile forming yarns in the production of a homogeneous pile tread surface, the combination of a steaming and moistening chamber, means for advancing the carpet or rug through said chamber to condition the pile, a support and a felting platen at the exit end of said chamber between which the carpet or rug is passed as it is fed from the chamber, shafts mounted on the 15 machine frame above the platen and having eccentrics, connections between the eccentric and the platen for supporting the weight of the platen that it may act upon the pile surface in like contact therewith, and means for operating the 20 eccentrics to impart a light felting action to the platen that causes the end portions of the pile forming yarns to be permanently felted together without crushing or matting effect.
- 25 2. In a machine of the character described for treating pile carpets and rugs, the combination of a steaming and moistening chamber, means for feeding a carpet or rug through the steaming and moistening chamber to condition it, a yielding support outside of and adjacent the exit of the 30 steaming and moistening chamber over which the heated and moistened carpet or rug is passed, a platen above the yielding support, and means above the platen and between its ends for supporting it with light contact on the pile surface

and for imparting a light felting action to the platen to felt the pile yarns together and produce a homogeneous pile surface without crushing or matting effect.

3. In a machine for finishing the pile surface of carpets and rugs, the combination of a steaming and moistening chamber, means for feeding a carpet or rug through said chamber that the steam may pass through the carpet or rug to condition it, a support and an opposed platen outside of and closely adjacent the exit of the steaming and moistening chamber between which the carpet or rug is progressively fed, and means above and between the ends of the platen for sustaining the weight thereof and for imparting a rotary reciprocating movement to the platen in light contact with the pile to felt the heated and moist fibres of the pile permanently together without crushing or matting effect as the carpet or rug emerges from the steaming and moistening chamber.

4. In a machine for finishing the pile surface of carpets and rugs, the combination of a steaming and moistening chamber, means for feeding a carpet or rug through said chamber to condition the pile for felting, a support at the exit of the chamber over which the moist and heated carpet or rug is passed as it emerges from said chamber, a platen opposed to said support, a plurality of blocks mounted on the upper side of the platen and having eccentric bearings, eccentrics operating in the bearings of said blocks, shafts carrying the eccentrics, and a plate or overhang engaging the upper surface of each eccentric and secured to the platen whereby the weight of the platen is supported by the eccentrics and their shafts so that a light felting action may be imparted to the end portions of the pile without crushing or matting effect.
